UNITED STATES PATENT OFFICE.

HARRY A. KUHN, OF PITTSBURGH, PENNSYLVANIA.

METHOD OF MINING COAL.

1,237,063.

Specification of Letters Patent. Patented Aug. 14, 1917.

Application filed May 18, 1914. Serial No. 839,330.

To all whom it may concern:

Be it known that I, HARRY A. KUHN, a citizen of the United States, and resident of Pittsburgh, in the county of Allegheny and 5 State of Pennsylvania, have invented a new and useful Improvement in Methods of Mining Coal; and I do hereby declare the following to be a full, clear, and exact description thereof.

10 My invention relates to method of mining coal.

The object of my invention is to provide a method of disrupting or breaking up a mass of coal in its original bed by the use of explosives, the operation being carried on in such a way that the coal is not blown to small bits or atoms, and so torn and disrupted by the explosion as to produce a powder or slack coal, but in which the coal is split 20 along its natural lines of cleavage, and then further separated, so that the solid wall of coal is broken up into lumps of large size which may be readily removed by a suitable digging and conveying apparatus, or even 25 may be removed by a pick and loaded by hand upon the pit cars in the manner most commonly employed.

To these ends my invention consists, generally stated, in making a kerf in the solid 30 wall of coal and inserting explosive material into this kerf, drilling into the solid wall removed from the kerf in the usual way, shooting this coal so that the coal is separated along its lines of cleavage and settles 35 into said kerf, and finally setting off the first charge inserted in the undercut, whereby the coal is further disrupted and separated, the force last applied being preferably directed upwardly, or outwardly, so as to give the 40 desired effect of separating the coal into lumps, so that it may be readily dislodged and carried away.

In the accompanying drawings, Figure 1 is a view of a body of coal under which an 45 undercut has been made and the explosive inserted in the undercut; Fig. 2 is a like view showing the wall of coal after the first shooting operation; Fig. 3 is a like view after the second shooting operation; Fig. 4 is an enlarged detail of the form of torpedo 50 employed by my process, and Fig. 5 is a face view of coal showing the torpedo in position in the undercut and the hole drilled for the insertion of the explosive to cause 55 the first shooting of the coal.

In carrying out my improved method the

wall of coal 2 which is to be mined, is first undercut as at 3, this undercutting being done by any suitable kerf cutting machine. After the undercut has been made, the torpedo or other explosive device 4 is inserted in the undercut. This torpedo comprises the lower cupped portion 5 which contains a suitable explosive 6 and covering the cup 5 is the cap or cover 7 which fits loosely over 60 the cup 5 and leaves a space 8 between the inside of the cap and the outside of the cup for the passage of the wires 9. The upper edge of the cup is also provided with the opening 10 through which the wires pass 70 into the cup, and the wires are connected with the percussion-cap 11. In the drawing I have illustrated these torpedoes as round in shape, and, as shown in Fig. 5, they are arranged at intervals in the rear of the undercut, and in order to get the full effect of 75 the action of the torpedoes I connect each pair with a plate 12 which acts to distribute the effect of the explosion along practically the entire width of the undercut, as will 80 more fully hereinafter appear.

After the torpedoes have been inserted in this manner within the undercut, the holes 13 are drilled in the wall of coal at a suitable height preferably extending slightly 85 upwardly as indicated in Fig. 1 and when said holes have been drilled, they are charged with powder or other suitable explosives.

With these preliminary preparations, the 90 charge of powder in the holes 13 is set off and this charge is of such strength as to separate the coal along its lines of cleavage without breaking it up into small particles, the coal after this first explosion settling down to 95 substantially the position indicated in Fig. 2, thereby filling up the original undercut 3. The torpedoes 4 are then set off and the wires 9 extend off to a suitable point of safety, where by simply throwing a switch, 100 the circuit is completed and explosion of the torpedoes 4 takes place. As the torpedoes are inclosed by the mass of coal on all sides, and as the tops or covers 8 are movable, the line of least resistance is upwardly and accordingly an upward force is applied which being distributed by the plates 12 across the cut, acts to disrupt the mass of coal further and separate the coal into large lumps in substantially the manner indicated in Fig. 3. 110

In case there are any bands of slate 15, such as indicated in Fig. 5, and these bands

of slate are not broken up by the first explosion, the second explosion will act to break up said bands and so prevent the bridging of the coal above the same, and the 5 difficulty of its removal by the machine.

With the coal in this condition, the removal of it can be accomplished in any suitable manner, but I prefer to employ the mining machine, such as shown and described in 10 an application filed of even date herewith, Serial No. 839,326, and a portion of which is indicated in Fig. 3. This machine is adapted to advance along the original floor of the mine and the undercut, and digging under 15 the coal which has been acted on in the above manner, the coal is moved onto the conveyer and by the conveyer moved back to the pit car in the rear. By simply separating the coal along its lines of cleavage by 20 the first shooting operation and by following that up by a disrupting force originat-

ing within the mass of coal first shot in this manner, the disrupting force in no case is sufficient to disintegrate the coal into slack or pulverulent form, but the coal is left in 25 large lumps which can be readily removed either by machine or by hand, if so desired.

What I claim is:

The method of mining coal consisting in forming a kerf in the wall of coal, inserting an explosive in said kerf, shooting the wall of coal at a point removed from said kerf whereby the coal is separated along its lines of cleavage and settles into the kerf, and subsequently setting off the explosive inserted within said kerf. 30 35

In testimony whereof, I the said HARRY A. KUHN have hereunto set my hand.

HARRY A. KUHN.
